(57) **CLAIM**

We claim the ornamental design for a vibration device, as shown and described.

DESCRIPTION

FIG. 1 is an isometric view, from the bottom right, of the vibration device in an exploded configuration.

FIG. 2 is an isometric view, from the top left, of the vibration device in the exploded configuration.

FIG. 3 is an elevation view from the right side of the vibration device in the exploded configuration.

FIG. 4 is an elevation view from the left side of the vibration device in the exploded configuration.

FIG. 5 is an elevation view from the front of a first, second, and third component of the vibration device.

FIG. 6 is an elevation view from the back of the first, second, and third component of the vibration device.

FIG. 7 is a plan view from the top of the vibration device in the exploded configuration.

FIG. 8 is a plan view from the bottom of the vibration device in the exploded configuration.

FIG. 9 is an isometric view, from the top right, of the vibration device in the assembled configuration; and,

FIG. 10 is an isometric view, from the top right, of a second variation of the vibration device in the assembled configuration.

1 Claim, 10 Drawing Sheets
